Primary Examiner — Mitchell I. Siegel

(57) **CLAIM**

The ornamental design for a swing, as shown and described.

DESCRIPTION

FIG. 1 is a perspective view of a swing showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines throughout the drawing figures depict portions of the swing that form no part of the claimed design. Any portion of the article between the break lines forms no part of the claimed design.

1 Claim, 7 Drawing Sheets(56)
